UNITED STATES PATENT OFFICE.

LEWIS B. WISMER, OF READING, PENNSYLVANIA.

SAUCEPAN.

SPECIFICATION forming part of Letters Patent No. 638,307, dated December 5, 1899.

Application filed September 22, 1899. Serial No. 731,343. (No model.)

To all whom it may concern:

Be it known that I, LEWIS B. WISMER, a citizen of the United States, residing at Reading, in the county of Berks and State of Pennsylvania, have invented a new and useful Saucepan, of which the following is a specification.

The invention relates to improvements in saucepans.

The object of the present invention is to improve the construction of saucepans and analogous utensils and to provide a simple, inexpensive, and efficient one, adapted to be automatically opened by the ebullition of its contents to permit the escape of steam and capable of preventing its contents from escaping and running over upon the stove or other heating apparatus and causing disagreeable odors.

A further object of the invention is to provide a hinge connection between the cover and the body of a saucepan or other vessel, adapted also to serve as a handle for opening and closing the lid or cover.

The invention consists in the construction and novel combination and arrangement of parts hereinafter fully described, illustrated in the accompanying drawings, and pointed out in the claims hereto appended.

In the drawings, Figure 1 is a perspective view of a saucepan constructed in accordance with this invention. Fig. 2 is a vertical sectional view of the same.

Like numerals of reference designate corresponding parts in both figures of the drawings. 35 1 designates a saucepan provided at its top with an inclined portion or flange 2, forming a flaring mouth and extending above the disk-shaped lid or cover 3, to provide a receptacle of increased capacity for the purpose of preventing the escape of any of the contents of the receptacle during ebullition and to avoid the disagreeable odors resulting from such

contents coming in contact with the stove or other heating apparatus. The upper edge of 45 the inclined flange 2 is strengthened by a bead 5, consisting of sheet metal and a strengthening-wire 6. The sheet metal of the flange is rolled around the wire, and it is cut away at 7 to expose a portion of the wire of the bead

50 to enable the same to serve as a pintle for hinging the lid 3 of the receptacle. Secured to the center of the lid is a substantially L-

shaped rod 8, composed of a short approximately vertical arm and a long horizontal arm extending from the center of the lid to 55 the cut-away portion of the flange and provided therewith an eye 9, through which the eye 6 passes. The eye 9 is formed by coiling or bending the rod on itself, as clearly illustrated in Fig. 2, and the lower end 10 of 60 the short arm is bent at an angle and secured to the center of the lid. The rod which extends horizontally from the flange is arranged within easy reach and forms a convenient handle adapted to be readily grasped by the 65 operator in opening and closing the receptacle. During the ebullition of the contents of the pan the cover or lid 3 is lifted vertically, and its entire edge or periphery is separated from the adjacent surface of the receptacle to provide an escape for steam at all 70 points, and the inclined flange, which extends above the cover, will prevent the contents from escaping and coming in contact with the stove or heating apparatus, and all disagreeable odors resulting from such contact 75 will be avoided.

Although the improvements are shown applied to a saucepan in the accompanying drawings, it will be readily apparent that they are 80 applicable to all kinds of receptacles employed for boiling their contents, such as clothes-boilers, coffee-pots, teapots, tea-kettles, and the like. It will also be apparent that the device is exceedingly simple and inexpensive in construction and that the cover, which is automatic in its operation, will rise and fall as the boiling increases and diminishes and that the inclined flange will effectually prevent the escape of the contents of 85 the receptacle. Furthermore, the hinge member, which connects the lid with the body of the receptacle, serves as a handle for opening and closing the latter.

Changes in the form, proportion, size, and 95 the minor details of construction within the scope of the appended claims may be resorted to without departing from the spirit or sacrificing any of the advantages of this invention.

What is claimed is—

1. A device of the class described comprising a receptacle provided at its top with an inclined flange forming a flaring mouth, a

- cover consisting of a disk arranged within the receptacle and supported at the base of the said flange, and a connecting-piece extending from the cover to the upper edge of the flange and hinged to the latter, whereby the cover is adapted to swing upward bodily to carry its entire periphery away from the supporting-surface, substantially as and for the purpose described.
- 10 2. A device of the class described comprising a receptacle, a cover supported within the receptacle at a point below the upper edge thereof, and a connecting-rod hinged to

the upper edge of the receptacle and extending inward therefrom over the cover and secured to the latter, said rod forming a hinge connection and serving as a handle for the cover, substantially as described.

In testimony that I claim the foregoing as my own I have hereto affixed my signature in the presence of two witnesses.

LEWIS B. WISMER.
